FOREIGN PATENT DOCUMENTS

GB 6058800 4/2019

Primary Examiner — Katie Jane Stofko(74) *Attorney, Agent, or Firm* — W&C IP(57) **CLAIM**

The ornamental design for a microphone windscreen, as shown and described.

DESCRIPTION

FIG. 1 is a perspective view of a microphone windscreen; FIG. 2 is a front elevational view of the microphone windscreen, a rear elevational view of the microphone windscreen being mirror symmetrical to the front elevational view;

FIG. 3 is a top plan view of the microphone windscreen, a bottom plan view of the microphone windscreen being mirror symmetrical to the top plan view;

FIG. 4 is a right side elevational view of the microphone windscreen;

FIG. 5 is a left side elevational view of the microphone windscreen; and,

FIG. 6 is a sectional view of the microphone windscreen taken along line 6-6 of FIG. 3.
